(57) **CLAIM**

The ornamental design for “a computer”, as shown and described in FIGS. 1-15.

DESCRIPTION

FIG. 1 is a front, bottom, right perspective view of a computer, showing our new design;

FIG. 2 is a front elevation view of the computer of FIG. 1;

FIG. 3 is a rear elevation view of the computer of FIG. 1;

FIG. 4 is a top plan view of the computer of FIG. 1;

FIG. 5 is a bottom plan view of the computer of FIG. 1;

FIG. 6 is a left side elevation view of the computer of FIG. 1;

FIG. 7 is a right side elevation view of the computer of FIG. 1;

FIG. 8 is an exploded perspective view of the computer of FIG. 1;

FIG. 9 is a rear, perspective view of the computer of FIG. 1 in a first environment;

FIG. 10 is a front, left perspective view of the computer of FIG. 1 in a second environment;

FIG. 11 is a rear, left perspective view of the computer of FIG. 1 in a third environment;

FIG. 12 is a rear, left perspective view of the computer of FIG. 1 in a fourth environment;

FIG. 13 is a rear, left perspective view of the computer of FIG. 1 in a fifth environment;

FIG. 14 is a front, left perspective view of the computer of FIG. 1 in a sixth environment; and,

FIG. 15 is a rear, left perspective view of the computer of FIG. 1 in a seventh environment.

The dotted broken lines show features of the computer that form no part of the claimed design.

The dashed broken lines show environment that form no part of the claimed design.

1 Claim, 15 Drawing Sheets
